UNITED STATES PATENT OFFICE.

ARTHUR WILLIAM RAMMAGE, OF EAST PUTNEY, LONDON, ENGLAND, ASSIGNOR TO THE
CHAPMAN TROUGH DECKING COMPANY LIMITED, OF LONDON, ENGLAND.

METAL FLOORING.

1,235,054.

Specification of Letters Patent.

Patented July 31, 1917.

Application filed August 24, 1914, Serial No. 858,305. Renewed March 28, 1917. Serial No. 158,112.

To all whom it may concern:

Be it known that I, ARTHUR WILLIAM RAMMAGE, of East Putney, London, S. W., England, have invented a Metal Flooring, 5 of which the following is a specification.

This invention has for its object a trough flooring or decking for bridges, piers, subways, culverts, buildings, and the like. I am aware that it has been previously proposed, in the construction of ships and other structures to make use of channel section plates exactly similar in form to one another, the flanges of the channels serving as means for riveting the several plates together and also serving the purpose of ribs or frames.

I am furthermore aware that it is not new in decking or flooring to construct plates of the ridge and furrow type which are similar 20 in form to one another and provided with flanges at their ends which are either vertically or horizontally disposed and joined and riveted together with or without angle or T-irons.

25 I desire it to be understood that I make no claim to the employment of ridge and furrow decking or flooring but confine myself to the invention of such a section thereof as shall allow of being machine or hand riveted or bolted together from above in the case of bridges and floors and from below in the case of ceilings for subways and at the same time permit of the edges of the joint being kept below or above the general 30 level of the deck as the case may be.

Moreover only one single form of section is used, which can be pressed out of flat plates to shape. The said shape when formed is that of one or more corrugations 40 the lower ones being trough shaped with preferably a flat bottom and the sides or webs widening at the top. The several sections are moreover so constructed and arranged that, when erecting the flooring or 45 decking, no under stages are necessary as all the riveting may be done at the top by any suitable known machine riveter. Furthermore, a minimum of riveting and metal is necessary and, since no rivets or flanges 50 project above the deck obvious advantages are gained. Another feature of this invention is that the sections are easily and cheaply manufactured, and that they pack well for shipment.

55 To obtain these purposes my invention

consists in providing a trough flooring or decking constructed of identical corrugated sections of plate characterized by the fact that both ends of each section are terminated by flanges and that one of the said 60 flanges is separated from the adjacent portion of the plate by a minor corrugation so designed as to insure that the two flanges are parallel to one another and also that their tops are not above the level of the 65 highest portion of the plate. The flanges or adjacent sections of plate will thus be parallel, and such flanges are so disposed as to be capable of being readily riveted from the top without the employment of 70 understaging. The said flanges should be either vertical, or should be inclined, in a direction away from the said minor corrugation, at such an angle to the vertical as will afford sufficient clearance for the opera- 75 tion of riveting, but not at a greater angle to the vertical than will bring them parallel to the opposite web or side of the main corrugation to which such flanges are next adjacent. A greater inclination would ob- 80 viously cause a difficulty in stamping the plates, as the flange would overhang and prevent the withdrawal of the die.

It will be apparent that if flooring made according to my invention is used as a roof 85 or ceiling for subways, it may be reversed, and in that case all riveting may be effected in like manner from one side only—in this case the underside.

In order that my invention may be more 90 clearly understood, reference is made to the accompanying drawing, in which:—

Figure 1 shows a perspective view of a first form of construction of the flooring or decking with several sections joined together;

Fig. 2 shows a cross section of a modification, this form of construction being adapted for use with smaller or lighter 95 floorings or decking.

Fig. 3 shows a cross section of another modification particularly useful for heavy constructions, that is, for such that are subjected to great strain;

Fig. 4 shows a cross section of a third 105 modification.

To carry out my invention, Fig. 1, I make provision of a series of sections *a* of precisely similar shape, the said sections being adapted to be pressed out of flat plates of 110

steel, iron or any other suitable material or metal. The shape of each section when formed is, as has already been indicated, that of two corrugations, the lower one being 5 trough-like with a preferably flat bottom as shown at α^1 , and the sides or webs α^2 and α^3 widening out toward the top.

At the top of the left-hand side web α^2 a flange α^4 is formed by bending the web inward until vertical or even parallel with the 10 right-hand side web of the trough.

It will be easily understood that the flange may be at any intermediate angle.

The right-hand side web continues curved 15 over to form the top corrugation or deck which may be flat in the center, and then curves in a minor corrugation so as to end in a flange α^5 which is parallel to the left hand flange α^4 .

20 These flanges are riveted or bolted together at b , and the top of the flange is slightly below the deck or head of the top corrugations.

According to the modification, Fig. 2, the 25 sections c consist of a series of four corrugations with a comparatively small depth, this form of construction being suitable for light flooring or decking. The arrangement of the flanges d , d^1 and the manner of joining

30 the sections is substantially the same as described with reference to Fig. 1. It will be easily understood that three or four or more corrugations may be formed in one section. These corrugations, if the structure described 35 is used as a floor or decking may be filled in the known manner with concrete or ballast.

According to the second modification, Fig. 3, the sections e are made of stronger plates 40 and the depth of the corrugations is considerably greater. This construction is adapted for use with heavy flooring or decking, the flanges f , f^1 in this case also being arranged and joined in the manner previously 45 described.

In every form described the ends of said flanges are slightly below the level of the top

corrugations, and in every case the flanges on the left-hand side web of the corrugation are either vertical, Fig. 4, or parallel with 50 the right-hand web of said corrugation, this arrangement not only allowing of easy packing for shipping purposes but also facilitating the pressing process.

An end view of a length of decking made 55 to the section above described would correspond with the attached drawing when viewed only from one end.

Seen from the other end what was described above as right hand would be left 60 hand and vice-versa.

Having now fully described my said invention what I claim and desire to secure by Letters Patent is:—

1. In a trough flooring or decking for 65 bridges and the like, the combination of identical corrugated sections of plate, both ends of each section being terminated by flanges one of which is separated from the adjacent portion of the plate by a minor corrugation so designed as to insure that the two flanges are parallel to one another and that their tops are not above the level of the highest portion of the plate, substantially as 70 and for the purpose set forth.

2. In a trough flooring or decking for 75 bridges and the like, the combination of identical sections of plate of which each is provided with a plurality of corrugations having flat tops and bottoms and both ends 80 of each section being terminated by parallel flanges and of which the tops do not project above the tops of said corrugations and of which flanges one is separated from the adjacent portion of the section by a minor corrugation, substantially as and for the purpose described.

In testimony whereof I have hereunto set my hand in the presence of two subscribing witnesses.

ARTHUR WILLIAM RAMMAGE.
